STAPLING AND TACKING MACHINE

Augie L. Hansen, Chicago, Ill., assignor to A. L. Hansen Mfg. Co., Chicago, Ill., a corporation of Illinois

Application February 15, 1936, Serial No. 63,996

9 Claims. (Cl. 1—49)

This invention relates to staple driving machines of the tacker type and consists of the matters hereinafter described and more particularly pointed out in the appended claims.

The subject matter of the present invention is illustrated herein as applied to a stapling or tacking machine of the type disclosed in the patent to Hugo J. Baur, No. 1,978,983, October 30, 1934. In such machine, particularly when designed as a tacker, where the staple is driven its full length, without clinching, into wood, hard fiberboard, or like tough, resistant material, the driving member or plunger, arrested in its full driving movement at the end of its stroke by parts of the base of the tacker, produces such pounding against said parts, made necessarily of light metal, with a resulting vibration, that crystallization of the metal of said parts soon follows and breakage occurs. The life of such stapling machine and/or tacker is thus greatly shortened and repairs or renewal are difficult and expensive.

The object of the present invention is to provide a stapling machine or tacker of the kind, with parts so constructed and combined that said pounding, with resultant crystallization of parts, will be relieved and/or compensated for, so that there will be little or no such crystallization, with the result that the life of the machine is greatly extended.

The advantages of the invention will appear more fully as I proceed with my description of the improvements in detail.

In the drawings:—

Figure 1 is a perspective view of a stapling or tacking machine embodying the invention;

Figure 2 is a view representing a longitudinal vertical section through the machine in a median vertical plane thereof, with the parts in normal position;

Figure 3 is a similar view with the plunger driving member withdrawn to the position where it is released for driving the staple;

Figure 4 is a vertical section of the machine in a plane indicated by the line 4—4 of Figure 3;

Figure 5 is a partial section of the machine in a plane indicated by the line 5—5 of Figure 3, with the parts shown in the position when the driving blade has driven the staple almost to the position of engagement with the article into which the staple is to be driven;

Figure 6 is a section in a plane indicated by the line 6—6 of Figure 3, with the parts in position as when the plunger has completed its stroke to drive the staple home, with the driving blade

Figure 7 is a perspective view of a yoke used in the construction;

Figure 8 is a perspective view of a pad designed to receive the direct shock at the end of the stroke of the hammer; and

Figure 9 is a view representing a cross section through the base of the stapling machine in a plane indicated by the line 9—9 of Figure 1.

Referring now to that embodiment of the invention illustrated in the drawings:—10 indicates the base of the improved staple driving or tacking machine; 11 indicates a handle carried thereby; 12 indicates a tubular head at the driving end of the base, which head houses the driving plunger and the spring for driving it and provides an abutment for the top end of said spring; 13 indicates an operating lever to be gripped by the palm of the hand with the fingers engaged below the handle 11 when operating the plunger to drive a staple; 14 indicates a spring-controlled linkage connecting the lever 13 to a pawl 15 which raises the plunger and releases it at a predetermined point; and 16, 16 indicate spaced, upright wings extending rearwardly from the head 12, which wings provide support for the lever 13, the linkage 14 and pawl 15, and have an arbor on which is mounted the coiled spring 17, which acts to feed the staples to be driven.

The base 10, as shown, comprises a shell or shoe 23 and a housing including channel plates 19, 19 and 19a, 19a, which provide the horizontal way through which the staples are fed to the vertical driveway between front and rear jaws 20, 21 fixed to the front end of the channel bars 19, 19. 22 indicates the driving blade depending from the plunger and operating through said vertical driveway. The shoe 23 of the base 10 is in the form of a channel bar having a bottom wall 24 and upright side flanges 23a, 23a. The tubular head 12 is open at the top end 12a, which is closed by a tubular cap 26 telescoped thereon. 27 indicates a coiled spring interposed between the top end 26a of the cap 26 and the top end 12a of the tubular head 12.

28 indicates the driving plunger, to the bottom end of which is fixed the driving blade 22. Said plunger has a vertical stem 29 which is preferably slidable within a guide tube 30 having a top flange 30a. 31 indicates a heavy coiled spring interposed between the top end of the cap 26 (which provides its top seat) and the top of the plunger 28. The intermediate flange 30a of the guide tube 30, which directly seats the spring, is centered by a central depression 26b in the top end 26a of said cap. 32 indicates

a yoke having a cross member 32a engaged with the top 26a of the cap 26 and having its legs 32b, 32b extended down at the sides of the head 12 towards the base 10. Said legs are pivotally connected at their bottom ends by a pin and slot connection 33, 33 to upwardly projecting ears 34, 34 rising from the forward ends of the side flanges 23a, 23a of the shoe 23. The slots are for the purpose of depressing the yoke to remove the cap when assembling or replacing the springs in the head 12. The bottom wall 24 of the base is notched out at its forward end, as indicated at 35 (see Figures 2 and 4) to permit the front and rear jaws 20 and 21, with the passageway therebetween, to project down through said bottom wall so as to terminate in the plane of the bottom face of said base.

The head 12 and the wings 16, which provide support for the lever 13, the linkage 14, the plunger raising pawl 15, the arbor for the coiled feed spring 17 and the forward end of the handle 11,—are made rigid with and are preferably integral with laterally spaced bars 18, 18 (see Figures 4, 5 and 6) which extend longitudinally 25 of the base 10 between the upright side flanges 23a, 23a of the base shoe 23 and the respective proximate flanges of the channels 19, 19 which form part of the housing for the horizontal feed-way for the staples. Said bars 18, 18 are pivoted 30 at their rear ends to the rear ends of the side flanges 23a of said shoe by transverse bolts 25, 25, so as to be hinged to the base at its rear end on an axis extending transversely of said base. The rear end of the handle 11 is also 35 pivoted to said base on one of said bolts 25. The bars 18, 18 have horizontal flanges 18a, 18a which overlie the channels 19, 19.

A pad 36 (shown in perspective in Figure 8) is mounted at the front end of the base on the 40 channel bars 19 in position to receive the blow of the plunger 28 when it reaches the end of its downward driving movement, as shown in Figure 2. Said pad is in the form of part of a circular disk inserted back of the path of said 45 plunger, where it is held in place by a rivet pin 36b.

From the foregoing description, it will be observed that the tubular head 12, the supporting wings 16, the handle 11 and the bars 18 together 50 constitute a unit frame which is movable upon an axis transverse of the base 10 provided by the bolts 25 at the rear end of said base. Thus the head 12, the bottom end of which is normally in contact with the top of the base 10, 55 as at 12x, (see Figures 1, 2 and 3) is movable with said frame relative to the base 10 at that point.

The operation of the device is as follows:— When a staple is to be driven, the stapling machine is brought to proper position with the bottom wall of the base in contact with the surface into which the staple is to be driven. The lever 13 is then operated to raise the plunger 28 to the upper limit of its movement, where 60 it is released by the disengagement of the pawl 15. In this movement of the plunger the driving spring 31 is compressed, as indicated in Figures 3 and 4. Upon the release of the plunger the blade 22 is driven down through its passageway to drive the staple with the force resulting from the expansion of the coiled spring 31.

The plunger 28 is arrested at the end of its stroke by the pad 36 carried at the front end 70 of the base 10, to which the shock of the blow

is transmitted through said pad. At this time, the plunger actuated spring 31 is expanded, as shown in Figure 6, but is still under compression. Since the cap 26, which acts as an abutment to resist the upward thrust of the spring 31, 5 is connected by the yoke 32 to the shoe 23 of the base 10, the reaction resulting from the shock due to the sudden arrest of the plunger, is to an extent absorbed and reduced through the plunger 28 by the driving spring 31. In 10 addition, said reaction of the base is communicated at 12x to the tubular head 12 in such manner as to swing the whole frame including the bars 18 upon the axis of the bolts 25. The inertia of said head 12 and the frame carrying 15 it and the friction between said frame and the base are opposed to such movement and act to absorb and reduce to a minimum any chattering or vibratory reaction between the plunger 28 and the base or its parts, which might otherwise result in crystallization of the parts comprising the base.

The movement of the head 12 with reference to the base 10 and the plunger 28, held in engagement with the base by the expanded spring 31, is independent of the plunger and base and is difficult of observation when the staple driving machine is normally operated. But that such relative movement occurs is evidenced by the fact that the coiled spring 27 interposed 30 between the cap 26 and the top end of the tubular head 12 is required in order to restore the head 12 and the frame of which it is a part, to their original position before the normal operation of the staple driving machine may be 35 repeated.

I claim as my invention:—

1. In a staple driving machine, including a base, a reciprocable plunger, a spring for actuating said plunger, a seat for said spring, means rigidly connecting said seat to said base, and a frame including a tubular head in which said plunger is reciprocable, said head being normally engaged with said base but being movable with said frame relative to said base, and means for normally 45

2. In a staple driving machine, including a base, a reciprocable plunger, a spring for actuating said plunger, a seat for said spring, means rigidly connecting said seat to said base, a frame including a tubular head in which said plunger is reciprocable, said head being normally engaged with said base but being movable with said frame relative to said base, and means for normally maintaining said head in engagement with said base. 50

3. In a staple driving machine, including a base, a reciprocable plunger, a spring for actuating said plunger, a seat for said spring, means rigidly connecting said seat to said base, and a frame including a tubular head in which said plunger is reciprocable, said head being normally engaged with said base but being movable with said frame relative to said base about an axis transverse to the line of reciprocation of said plunger and remote 60 therefrom. 65

4. In a staple driving machine, including a base, a reciprocable plunger, a spring for actuating said plunger, a seat for said spring, means rigidly connecting said seat to said base, a frame including a tubular head in which said plunger is reciprocable, said head being normally engaged with said base but being movable with said frame relative to said base about an axis transverse to the line of reciprocation of said plunger and remote 70

therefrom, and means for normally maintaining said head in engagement with said base.

5. In a staple driving machine, including a base, a reciprocable plunger, a spring for actuating said plunger, a tubular cap providing an abutment for said spring, means rigidly connecting said cap to said base, and a frame including a tubular head in which said plunger is reciprocable and which is movable relative to said cap, said head 10 being normally engaged with said base but being movable with said frame relative to said base about an axis transverse to the line of reciprocation of said plunger and remote therefrom.

15. 6. In a staple driving machine, including a base, a reciprocable plunger, a spring for actuating said plunger, a tubular cap providing an abutment for said spring, means rigidly connecting said cap to said base, a frame including a 20 tubular head in which said plunger is reciprocable and which is movable relative to said cap, said head being normally engaged with said base but being movable with said frame relative to said base about an axis transverse to the line 25 of reciprocation of said plunger and remote therefrom, and means for normally maintaining said head in engagement with said base.

7. In a staple driving machine, including a base, a reciprocable plunger, a spring for actuating said plunger, a tubular cap providing an abutment for said spring, a yoke connecting said cap to said base, and a frame including a tubular head in which said plunger is reciprocable, said 30

cap being telescoped upon said head, said head being normally engaged with said base but being movable with said frame relative to said base about an axis transverse to the line of reciprocation of said plunger and remote therefrom. 5

8. In a staple driving machine, including a base, a reciprocable plunger, a spring for actuating said plunger, a tubular cap providing an abutment for said spring, a yoke connecting said cap to said base, a frame including a tubular head 10 in which said plunger is reciprocable, said cap being telescoped upon said head, said head being normally engaged with said base but being movable with said frame relative to said base about an axis transverse to the line of reciprocation 15 of said plunger and remote therefrom, and means for normally maintaining said head in engagement with said base.

9. In a staple driving machine, including a base, a reciprocable plunger, a spring for actuating said plunger, a tubular cap providing an abutment for said spring, a yoke connecting said cap to said base, a frame including a tubular head 20 in which said plunger is reciprocable, said cap being telescoped upon said head, said head being 25 normally engaged with said base but being movable with said frame relative to said base about an axis transverse to the line of reciprocation of said plunger and remote therefrom, and an expansion spring interposed between said cap and 30 said head.

AUGIE L. HANSEN.
